(57) **CLAIM**

The ornamental design for a charging bowl for a portable digital audio player, as shown and described.

DESCRIPTION

This invention is related to a co-pending patent application, Ser. No. 29/213,910 entitled "Portable Digital Audio Player", filed Sep. 23, 2004.

FIG. 1 is a perspective view of the charging bowl for a portable digital audio player;

FIG. 2 is a front view thereof;

FIG. 3 is a top view thereof, with the bowl empty;

FIG. 4 is a top view thereof, with a portable digital audio player residing within the bowl;

FIG. 5 is a bottom view thereof;

FIG. 6 is a cross-sectional view taken along line VI—VI indicated in FIG. 4; and,

FIG. 7 is a cross-sectional view taken along line VII—VII indicated in FIG. 3.

The broken line showing of the portable digital audio player in FIGS. 4 and 6 is for illustrative purposes only and forms no part of the claimed design.
